United States Patent Office.

EGBERT W. SPERRY, OF WOLCOTTVILLE, CONNECTICUT.

Design No. 2,643, dated April 30, 1867.

DESIGN FOR A KNIFE, FORK, OR SPOON-HANDLE.

The Schedule referred to in these Letters Patent and making part of the same.

TO ALL WHOM IT MAY CONCERN:

Be it known that I, EGBERT W. SPERRY, of Wolcottville, county of Litchfield, and State of Connecticut, have produced a certain new and useful Pattern or Design for "Handle" for Knife, Fork, or Spoon; and I do hereby declare that the same is described and represented so as to enable others skilled in the art to make the same therefrom, reference being had to the drawings, and letters marked thereon which indicate like parts.

In the accompanying drawings, marked No. 3, *a* is a handle for knife, fork, or spoon. This handle is configurated with a single bead or thread, *a'*, and embellished with grape-vine *a''*, with foliage and cluster, to produce a rich pattern for a design for knife, fork, or spoon-handle.

What I claim, therefore, and desire to secure by Letters Patent, is—

The design for a "handle" for knife, fork, or spoon, substantially as shown and described.
